(57) **CLAIM**

The ornamental design for a bathroom scale with removable display, as shown and described.

DESCRIPTION

FIG. 1 is a top, front, and left side perspective view of the bathroom scale with removable display, with the removable display attached, showing my new design;

FIG. 2 is a top, front, and left side perspective exploded view thereof, with the removable display detached;

FIG. 3 is a front view thereof;

FIG. 4 is a back view thereof;

FIG. 5 is a top view thereof, with the removable display attached;

FIG. 6 is a left side view thereof, with the removable display attached, the right side view being the mirror image to the left side view;

FIG. 7 is a bottom view thereof; and,

FIG. 8 is a top, front, and left side perspective detail view thereof, showing the removable display detached.
